Des. 240,554
Patented July 13, 1976

240,554

DUPLICATING MACHINE WITH SORTER

Thomas R. Cross, Rochester, Clifford L. George, Macdon, and Jacob W. Pada, Fairport, N.Y., assignors to Xerox Corporation, Stamford, Conn.

Filed Nov. 22, 1974, Ser. No. 536,236

Term of patent 14 years

Int. Cl. D16—03

U.S. Cl. D16—36

FIG. 1

FIG. 3

FIG. 2

FIG. 4

FIG. 5

FIG. 1 is a front elevation of a duplicating machine with sorter showing our new design;

FIG. 2 is a right-side elevation thereof;

FIG. 3 is a left side elevation thereof;

FIG. 4 is a top plan view thereof; and

FIG. 5 is a rear elevation thereof.

We claim:

The ornamental design for a duplicating machine with sorter, as shown.
